TROWEL FOR PIPE LINING MATERIAL
Warren E. Perkins, Grand Island, N.Y., assignor to
Perkins Pipe Linings Inc., Grand Island, N.Y.
Filed Feb. 3, 1964, Ser. No. 342,031
4 Claims. (Cl. 25—38)

This invention relates to pipe lining apparatus wherein a protective coating of mortar or similar material in plastic condition is applied to the interior of a pipe and more particularly to a troweling means for smoothing the surface of such an interior coating directly after the same has been applied to or deposited against the interior wall of a pipe.

My prior Letters Patent No. 2,924,867, dated February 16, 1960 and No. 2,987,794, dated June 13, 1961, show troweling apparatus for this general purpose wherein the trowel device is adapted to be drawn through underground pipe and the former patent in particular shows apparatus for depositing a continuous layer of mortar against the interior of the pipe and for smoothing the same by directly following the depositing apparatus with a troweling device. The present invention provides a new and improved troweling means for use in a similar manner.

The prior art contains a number of examples of sheet metal frusto-conical trowels for the general purpose of smoothing an interior mortar coating by pulling the trowel through a pipe wherein such mortar has been applied to the interior surface of the pipe. The trowel is drawn through the pipe with its small end first and the large or trailing end of the trowel which performs the mortar-smoothing function is necessarily resilient and must be readily expandable and contractible in a diametral direction while still generally retaining its circular form or tending to maintain such form even though local conditions may cause the large troweling end of the trowel to assume somewhat elliptical or other distorted forms temporarily.

Since trowels of this type are drawn through a pipe under conditions where the operation of the trowel cannot be observed during its functional periods, the necessity for safe, accurate and foolproof operation and self-adjustment for various physical conditions which are encountered by the trowel in its passage through a pipe is of great importance.

The trowel of the present invention meets the unusual and demanding requirements of a satisfactory trowel for acting at the interior surfaces of pipes in a simple, effective and economical manner. In the trowel of the present invention a plurality of trowel plate segments are curved and formed in such manner that they combine to form a resiliently expandable frusto-conical trowel body.

As will appear later herein, the trowel plates of the trowel of the present invention are pivoted flatwise against each other at the small or leading end of the frusto-conical trowel body so that the leading end of the trowel is of a relatively fixed diameter and the large or troweling end is rendered automatically adjustable to varying diameters through relative pivotal movement of the trowel plates against each other at the small or leading end of the trowel to produce varying diameters at the large end of the trowel and correspondingly varying vertex angles of the frusto-conical trowel body.

Separate means are provided at the interior of the large or trailing end of the trowel body for resiliently urging overlapping portions of the trowel plates against each other despite relative intersliding movement of the plates at the large end of the trowel occasioned by diametral adjustment. Since the curvature of the flexible trowel plates at the large end of the trowel varies during troweling, the resilient means just referred to, which acts across

2

overlapping plate portions in a diametral direction, retains the overlapping plate portions relatively closely against each other during such adjustments in curvature and relative intersliding of the trowel plates while still maintaining circumferential continuity of the large end of the trowel.

In addition to this radially acting resilient means, the trowel of the present invention includes extension coil spring members located within the trowel body adjacent to its large end and acting across the overlapping plate portions in such manner that a pulling or extension spring force is caused to exert a resilient spreading force on the trowel plates at the overlapping portions thereof to yieldably urge the large end of the trowel body in a diametral-increasing direction. This means exerts resilient radially-outward trowelling pressure and allows for contraction and expansion of the large end of the trowel as conditions require.

The use of extension springs for this purpose instead of the usual compression springs is novel and important since the extension spring requires no guiding or retaining surfaces, the spring being suspended in space excepting where it ends connect with anchoring means carried by the trowel plates. Furthermore, the extension coil springs of the present invention are less subject to fouling due to their lack of lateral restraint or interference and also due to the fact that mortar which may enter between the coils of the spring will not prevent free extension of the spring. A further important feature of the extension coil spring trowel expansion arrangement of the present invention resides in the fact that expansion of the trowel under a fairly constant spring force is afforded through a relatively wide diametral range, as compared with prior art proposals of this general type.

A primary problem and consideration in the construction of a trowel of this general nature is to avoid conditions which permit mortar to enter between parts or in recesses of one kind or another, which mortar hardens and fouls the parts and prevents free relative resilient adjusting movements of the parts. The general manner in which the trowel plates of the present device are relatively supported, oriented and interconnected provides a structure which minimizes the possibility of the parts thus becoming fouled with mortar. The resilient means provided herein for preventing separation of the overlapped portions of the trowel plates, particularly at their trailing portions, without substantially modifying or affecting the basic resilient radial expandable relationship of the trailing portions of the plates, further contributes in an important manner to the general non-fouling structure of the trowel.

This is particularly important because of the "blind" or remote control conditions under which trowels of this nature are most often used. In ordinary use of a troweling device of this type obstructions within a pipe frequently bear locally against the troweling surfaces and if such as obstruction bears against the surface of a trowel plate adjacent to the area where such trowel plate underlaps the other plate, then the plates tend to separate in a radial direction and if such separation is permitted mortar inevitably enters the space created by such separation to a greater or less degree and prevents the parts from returning to proper overlapping condition even after the trowel has moved past the obstruction.

The arrangement of the present invention is such that separation of the plates as described above is effectively prevented and the overlapping parts of the trowel plates are held in intimate inter-sliding abutment even while such local distorting forces are applied thereto so that mortar cannot enter between the parts. The accomplishment of this relationship without substantially interfering with the free radial flexibility of the trailing end of

the trowel body is a very important improvement in devices of this type. Expansion and contraction thus take place without interrupting the continuous "closed loop" configuration of the trowel as viewed from its large end.

A single specific embodiment of the principles of the present invention is illustrated in the accompanying drawing and described in detail in the following specification. However, it is to be understood that such embodiment is by way of example only and that various mechanical modifications may be introduced without departing from the spirit of the invention, the scope of which is limited only as defined in the appended claims.

In the drawing:

FIG. 1 is a general somewhat schematic perspective view of one form of the trowel assembly of the present invention;

FIG. 2 is a side elevational view of the trowel body of FIG. 1;

FIG. 3 is an end elevational view of the trowel body of FIG. 2 viewed from the large or trailing end thereof;

FIG. 4 is an end elevational view of the trowel body of FIG. 2 viewed from the small or leading end thereof;

FIG. 5 is a fragmentary cross-sectional view on the line V—V of FIG. 3; and

FIG. 6 is a fragmentary cross-sectional view on the line VI—VI of FIG. 4.

Like characters of reference denote like parts throughout the several figures of the drawing and, referring particularly to FIG. 1, the numeral 10 designates generally a frusto-conical sheet metal trowel body having three rods 11 connected to the small end thereof and leading to a swivel member 12 which may be connected to any suitable traction means but is usually connected to a mortar applying machine in the manner illustrated in the above-enumerated prior patents whereby the trowel is drawn through the interior of a pipe immediately following the application of mortar to such interior.

The trowel body 10 may be made up of various numbers of individual trowel plates and in FIGS. 2, 3 and 4 the numeral 13 designates three individual trowel plates which overlap along longitudinal portions thereof to form the frusto-conical trowel body 10.

In FIG. 2 the numeral 15 designates the overlapping edge of one of the trowel plates 13 and the numeral 16 designates the underlapping edge of an adjacent trowel plate 13. The overlapped portions of adjacent trowel plates 13 are pivoted to each other adjacent to the small or leading end of the trowel body 10 by connections which may comprise headed studs 17 and washers 18 which are retained by peening or riveting the outer end of the shank of each stud 17. It will be noted that the shank portion of each stud extends through the overlapped layers of trowel plates 13 and pivots the adjacent plates to each other for relative intersliding movement. Thus the several trowel plates are free to move outwardly or inwardly at the large end of the trowel to increase or decrease the vertex angle of the frusto-conical trowel body 10.

Each trowel plate 13 is perforated adjacent to its small or leading end as at 20, the perforation 20 of each plate 13 being located approximately midway between the two pivotal connections 17, 18 of each plate 13. Screw and nut connections through the adjacent ends of the rods 11 and the perforations 20 connect the rods to the trowel body. In this way the tractive force is applied to the trowel body without tending to produce distortive effects upon the same.

The manner in which the overlapping portions of the trowel plates 13 are associated at the large end of the trowel body 10 to prevent separation of such overlapping portions while permitting expansive and contractive movements thereof will now be described. A screw 22 has its head portion 23 welded to the interior surface of the outer overlapping portion of each trowel plate 13. The shank portion of screw 22 projects radially inwardly

with respect to the trowel body, extending through a slot 24 in the underlying overlapped portion of the adjacent trowel plate 13, whereby the overlapping portions of the trowel plates may slide against each other in a circumferential direction.

A compression coil spring 25 is disposed about a bushing 26 on screw 22 and a pair of spring seat collars 27 and 28, likewise disposed about bushing 26, permit the coil spring to react between a nut 30 on screw 22 and, through the medium of washers 31, against the interior surface of the underlying trowel plate portion, thus urging the same against the overlying portion of the adjacent trowel plate to which screw 22 is welded.

A bracket 35 is welded to the interior surface of the underlying trowel plate portion and is slotted likewise as at 24 whereby screw 22 passes therethrough. Bracket 35 includes an upstanding end flange 36 to which one end of an extension coil spring 37 is attached, as clearly shown in FIG. 3. The opposite end of spring 37 is attached indirectly to the outer overlapping trowel plate portion, in the present instance, by connection with one of the washers 31 of screw 22 as by welding or the like.

Referring to FIG. 3 and particularly to the lower screw 22 and spring 37 thereof, it will be noted that the pull of the extension spring 37 acting against flange 36, tends to slide the underlying trowel plate portion 36 in a clockwise direction and tends to slide the outer or overlying trowel plate portion, through the medium of screw 22, in a counterclockwise direction. This tends to slide the plates in a diameter-increasing direction. This expansion movement will normally be limited by engagement of screws 22 in the ends of slots 24 and when the trowel is in use in a pipe, the diameter will normally be determined, yieldably, by the constriction imposed by the mortar against which the trowel is acting.

I claim:

1. Trowel means for smoothing a layer of plastic lining material in an interior generally cylindrical surface, said trowel means comprising a plurality of longitudinally extending overlapping plate members which combine to form a generally frusto-conical trowel body, said plate members having mounting means at the small end of the trowel body constraining said plate members to a relatively fixed diameter at such small end but permitting inward and outward movement of the plate members at the large end of the trowel body whereby the large end may expand and contract, means at the overlapping portions of said plate members adjacent to the large end of said body for resiliently retaining said overlapping portions against separation while permitting relative intersliding movement thereof to permit circumferential expansion and contraction of said large end, and expansion means at the large end of said trowel body at overlapping portions of adjacent plate member, said expansion means comprising means projecting inwardly from the inner overlapping plate portion, means projecting inwardly from the outer overlapping plate portion, said inner overlapping portion being slotted to permit circumferential movement of said last mentioned means relative to said inner overlapping portion, and a tension spring acting between said two inwardly projecting means to urge the edges of said inner and outer overlapping portions circumferentially toward each other to reduce the overlap and thus expand the large end of the trowel body.

2. Trowel means for smoothing a layer of plastic lining material in an interior generally cylindrical surface, said trowel means comprising a plurality of longitudinally extending overlapping plate members which combine to form a generally frusto-conical trowel body, said plate members having mounting means at the small end of the trowel body constraining said plate members to a relatively fixed diameter at such small end but permitting inward and outward movement of the plate members at the large end of the trowel body whereby the large end may expand and contract, and expansion means at the

large end of said trowel body at overlapping portions of adjacent plate members, said expansion means comprising means projecting inwardly from the inner overlapping plate portion, means projecting inwardly from the outer overlapping plate portion, said inner overlapping portion being slotted to permit circumferential movement of said last mentioned means relative to said inner overlapping portion, and a tension spring acting between said two inwardly projecting means to urge the edges of said inner and outer overlapping portions circumferentially toward each other to reduce the overlap and thus expand the large end of the trowel body.

3. Trowel means for smoothing a layer of plastic lining material in an interior generally cylindrical surface, said trowel means comprising a plurality of longitudinally extending overlapping plate members which combine to form a generally frusto-conical trowel body, pivot means connecting overlapping portions of adjacent plate members adjacent to the small end of the trowel body for relative intersliding pivotal movement on an axis generally perpendicular to the frusto-conical surface of the trowel body whereby the large end of the trowel body expands and contracts, means at the overlapping portions of said plate members adjacent to the large end of said body for resiliently retaining said overlapping portions against separation while permitting relative intersliding movement thereof to permit circumferential expansion and contraction of said large end, and expansion means at the large end of said trowel body at overlapping portions of adjacent plate members, said expansion means comprising means projecting inwardly from the inner overlapping plate portion, means projecting inwardly from the outer overlapping plate portion, said inner overlapping portion being slotted to permit circumferential movement of said last mentioned means relative to said inner overlapping portion, and a tension spring acting between said two inwardly projecting means to urge the edges of said inner and outer overlapping portions circumferentially toward

each other to reduce the overlap and thus expand the large end of the trowel body.

4. Trowel means for smoothing a layer of plastic lining material in an interior generally cylindrical surface, 5 said trowel means comprising a plurality of longitudinally extending overlapping plate members which combine to form a generally frusto-conical trowel body, pivot means connecting overlapping portions of adjacent plate members adjacent to the small end of the trowel body for relative 10 intersliding pivotal movement on an axis generally perpendicular to the frusto-conical surface of the trowel body whereby the large end of the trowel body expands and contracts, and expansion means at the large end of said trowel body at overlapping portions of adjacent 15 plate members, said expansion means comprising means projecting inwardly from the inner overlapping plate portion, means projecting inwardly from the outer overlapping plate portion, said inner overlapping portion being slotted to permit circumferential movement of said 20 last mentioned means relative to said inner overlapping portion, and a tension spring acting between said two inwardly projecting means to urge the edges of said inner and outer overlapping portions circumferentially toward 25 each other to reduce the overlap and thus expand the large end of the trowel body.
